FIG. 2.

WITNESSES:

A. B. Cornelius

Marie Mitchell.

INVENTOR:

Henry H. Talbot
BY Eugene Ayres.

ATTORNEY:

UNITED STATES PATENT OFFICE.

HENRY H. TALBOT, OF ST. JOSEPH, MISSOURI.

AUTOMATIC SELF-LOADING PISTOL.

1,137,173.

Specification of Letters Patent. Patented Apr. 27, 1915.

Application filed January 8, 1914. Serial No. 810,924.

To all whom it may concern:

Be it known that I, HENRY H. TALBOT, a citizen of the United States of America, residing at St. Joseph, in the county of Buchanan and State of Missouri, have invented certain new and useful Improvements in Automatic Self-Loading Pistols, of which the following is a specification.

This invention relates to an improvement in automatic self loading pistols and particularly to that class of re-coil operating arms in which the barrel has both a longitudinal and a vertical movement, said movements being guided by parallel links upon which the barrel is imposed and pivoted, or, in other words, my improvement relates to the class of fire-arms shown and described in the Letters Patent Number 580,924 granted by the United States Patent office to J. M. Browning April 20, 1897, and the Letters Patent granted to myself under Letters Patent Number 882,594, March 24, 1908, the manner of operating my trigger lock being simplified in my present invention over that shown and described in said Letters Patent heretofore granted me; this improvement is provided by a simple escapement movement by means of which the trigger is automatically locked after each separate discharge and only released when the moving parts have recovered from their re-coil movements and the breech block is again locked in position for another discharge.

I accomplish my object by the mechanism illustrated in the accompanying drawings, in which,

Figure 1 is a longitudinal section of the fire-arm, broken away, shown in firing position; Fig. 2 is a longitudinal section of the same, also broken away, shown partially open, the trigger lock in operation; Fig. 3 is a perspective of the trigger; Fig. 4 is a perspective of the trigger lock; Fig. 5 is a detail side view of a rear link provided with a cam, and Fig. 6 is a front view of the same.

Similar letters refer to corresponding parts throughout the several views, as follows:

A is the frame, B the breech-block, C the barrel, c' a split lug on the barrel which is perforated at c² where a rear link L is pivoted to it, said link being one of a pair (the other not shown) upon which the bar-

rel is supported and by which it is guided in its movements.

I is the trigger, i' is a bevel on the trigger, friction or pressure on which from a corresponding bevel h³ on the trigger lock controls and restrains it, i² is a countersink or slot in the top of the trigger which gives chamber to part of the trigger lock h⁴ suspended in the frame above it.

H is the trigger lock and h' is a perforation for its pivoting in the frame.

h² is an indentation in the lock which is immediately under a cam l' when the arm is in the closed or firing position, as shown in Fig. 1, which permits of a limited vertical movement of the lock.

h³ is a plane on the shank of the lock on which the cam l' treads while the barrel and breech-block are making their backward and forward movements, as shown in Fig. 2. h⁴ is a beveled shank which, when the cam l' is treading on the plane h³, is depressed and operating on the bevel i' of the trigger I, forces said trigger I forward and restrains it until said pressure is relieved.

l' is a cam on the lower end of rear link L or that part which is pinioned to the frame, the length of the link is such that when the barrel moves, it being pivoted to the other end of the link, it carries that end through a comparatively large arc merely rotating that end upon which is the cam.

From the foregoing description it will be seen that when the various parts are assembled in their respective positions, their operation is clearly shown as to wit, in the longitudinal section shown in Fig. 1, in closed or firing position the breech block B closed and the barrel C fully forward and elevated, the upper end of the link L drawn with it by the lug c' retiring the cam l' to its rearmost position over the indentation h² of the trigger lock H, thus permitting a limited vertical play of the wedge h⁴ so that it exerts no pressure on the bevel i', permitting a free horizontal movement of the trigger I; in the longitudinal section of Fig. 2 the arm is shown in a partially open or fired position, the breech block B receding from the barrel C which is depressed drawing the upper end of link L rearward and rotating the lower end on its pivot, thrusting forward cam l' into bearing on plane h³, de-

pressing wedge h^4 causing it to exert pressure on bevel i' , thereby forcing trigger I forward and restraining it until the parts have recovered and are in the position 5 shown in Fig. 1.

What I claim and desire to secure by Letters Patent, is,—

1. The combination in a magazine pistol with a frame, a recoiling barrel, a trigger 10 and a trigger lock, of a link pivoted at the upper end thereof to said recoiling barrel, a cam on the lower end of said link impinging on and co-acting with a plane on the upper surface of said trigger lock to depress said lock when the barrel 15 recoils.

2. The combination in a magazine pistol with a frame, a recoiling barrel and a trigger, of a link pivoted at its upper end to the recoiling barrel, a cam on the lower end

of said link, a trigger lock immediately 20 above the trigger and pivoted at its front end in the frame, a rearwardly extended shank, a plane on the upper surface of said lock, a notch in the upper surface of said shank providing a seat for the cam, a rearwardly and downwardly inclined surface bearing at the rear end of the lower face of 25 said shank on a similarly inclined surface on the trigger, said cam impinging on and co-acting with the plane on said trigger lock to depress said lock when the barrel 30 recoils.

In testimony whereof I affix my signature in presence of two witnesses.

HENRY H. TALBOT.

Witnesses:

WILLIAM E. HAWOOD,
CHARLES D. WURTZLER.
